UNITED STATES PATENT OFFICE.

JOHN M. SACKMAN, OF CARROLLTON, ILLINOIS.

SCAFFOLDING-BRACKET.

SPECIFICATION forming part of Letters Patent No. 767,768, dated August 16, 1904.

Application filed February 23, 1904. Serial No. 194,777. (No model.)

To all whom it may concern:

Be it known that I, JOHN MONROE SACKMAN, residing at Carrollton, in the county of Greene and State of Illinois, have invented new and useful Improvements in Scaffolding-Brackets, of which the following is a description, reference being had to the accompanying drawings, which are a part of this specification.

My invention relates to that class of scaffolding-brackets which grip the sides of a ladder or timber on which it may be necessary to erect scaffolds when building or painting; and the object of my invention is to provide a construction whereby the bracket holding the weight of the scaffolding-plank is gripped to the strongest part of the ladder and so gripped that it may be readily raised or lowered without removing the scaffolding-plank. This feature is most desirable, particularly in house-painting.

With the above primary object in view my invention consists of the devices and parts or their equivalents as hereinafter set forth.

In the accompanying drawings, Figure 1 is an elevation of my device gripped to the side of a ladder. Fig. 2 is an edge view of the lower grip with bar on which rides the scaffolding-plank. (Not shown.) Fig. 3 is a side view of the bar which carries scaffolding-plank, (not shown,) showing openings through the ends. Fig. 4 is an edge view of the upper grip; Fig. 5, an edge view of the notched bar, showing the fork and bolt passing through it. Fig. 6 is a top view of the bent rod with ends passing through the arched frame.

Referring to the drawings, the numeral 1 is a section of the stile of a ladder.

The letter *a* indicates the arched frame of the construction, having firmly attached thereto to the V-shaped gripping-plate *b*, (see Fig. 4;) *c*, the plate having rod *c'*, with its end bent to a right angle at *c'* extending inwardly, attached thereto, (see Fig. 2) *d*, the bar which carries the scaffolding-plank, (not shown,) said bar having in its ends openings through which the rod *c'* and bolt *g* pass, (see Figs. 2 and 3;) *e*, the bar provided with hooked notches *e'* passing through one edge; *f*, the fork (see Fig. 5) through which passes the bar *d* *g*, 50 the bolt (see Fig. 5) by which bars *d* and *e*

are pivoted together; *h*, the rod with ends bent to right angles, said ends passing through arched frame *a* (see Fig. 6) and securely attached thereto; *i*, the locking-plate, which is free to turn on arm of rod *h* at *j*. (See Fig. 6.)

To operate my device, I place the arched frame *a* so that the V-shaped gripping-plate *b* comes in contact with one side of the stile of a ladder and the rod *c'*, which extends inwardly from the plate *c*, comes in contact with the other side of the stile, as shown in Fig. 1. The bar *d* is then engaged with *c'* by passing the opening in the end of said bar over the bend at *c'*. (See Fig. 2.) The notched bar *e* is then passed through the opening between the bent portions of the rod *h* and one of the hooked notches *e'* engaged with the rod *h* at *j*. (See Fig. 6.) The forked end *f* is loosely engaged with the end of bar *d* by reason of the bolt *g* (see Fig. 5) passing through it. The locking-plate *i*, which is pivoted on the bent rod *h* at *j* (see Fig. 6) is then turned so that it will come in contact with the notched bar *e*, which will lock said bar *e* in its position. To raise or lower the scaffold, the operator simply grasps the arched frame *a* between the bar *e* and the side of the ladder and causes sufficient pressure to bear on the under side of said frame *a* to counterbalance the weight of the scaffolding-plank (not shown) resting on bar *d*, and this will free the gripping-plates *b* and *c*. Then by raising or lowering the bracket he will bring his scaffolding to the desired position. One of these brackets is necessary at each end of the scaffolding-plank. It is obvious that as the pitch of the ladder is necessarily changed it will of course be necessary to change the angle of the bar *d*, which holds the scaffolding-plank (not shown) in order that said plank may be kept at a right angle to the side of the building. To accomplish this, the operator after he has placed his ladder throws the locking-plate *i* out of engagement with the notched bar *e* and raises or lowers said bar *e* to another notch, which is then again hooked over bent rod *h* (see Fig. 6) at *j* and the locking-plate is again turned on its pivot *j*, which firmly locks bar *e*, as above set forth.

It will be noticed by referring to Fig. 1 of 100

the drawings that the bracket is gripped near the upper end and outside of the ladder, as the workman by lowering the bracket would soon become too far from his work to reach it conveniently. Said bracket can be very readily changed to the inside, when it will be gripped on the opposite stile of the ladder.

It is an obvious fact that the gripping power of my device is increased as the weight upon the scaffolding-plank is increased. Therefore the safety of said device is correspondingly increased.

Having thus fully described my invention, I claim as new and desire to secure by Letters 15 Patent—

1. The combination of the stile of a ladder 1, the arched frame or bar *a*, the gripping-plate *b* and the plate *c* attached thereto said plate *c*, having the rod *c'*, connected thereto 20 and means attached to this frame *a*, to carry the end of a scaffolding-plank as set forth.

2. In combination with the stile of a ladder 1, the arched frame or bar *a*, the gripping-plate *b*, formed in a V-shape plate, the plate 25 *c*, with the rod *c'*, extending inwardly, the bent rod *h*, with its arms *j*, *j'*, said arms passing through and firmly attached to frame *a*, the locking-plate *i*, pivoted at *j*.

3. In a scaffolding-bracket, the combination 30 with the stile of a ladder, of an arched frame, the gripping-plate, a rod attached to the lower plate and adapted to engage with the side of

the ladder, a bent rod with its arms fast to the overhanging ends of the frame, a locking-plate, a notched bar, one end of which passes 35 through an opening formed at the side of the overhanging end of the frame, the other end of said bar loosely attached to a bar on which rests a scaffolding-plank, and the other end of this bar engaged with the rod *c'* extending 40 from plate *c*, and adapted, so that when the notched bar is raised or lowered, different notches will engage with one end of the opening formed at the side of the overhanging end of the frame, the angle of the said bar carrying 45 the scaffolding-plank will be changed.

4. In combination with a ladder, the arched frame *a*, the gripping-plate *b*, and the plate *c*, with arm *c'* extending therefrom and adapted to rest against the stile of a ladder, the bent 50 rod *h*, the locking-plate *i*, the notched bar *e*, the bar *d*, all adapted substantially as set forth to carry a scaffolding-plank and to grip the stile of a ladder or timber in such a way that the whole construction may be readily raised 55 and lowered without removing the scaffolding-plank and also the angle of said plank may be changed as the "pitch" of the ladder is changed.

JOHN M. SACKMAN.
